Primary Examiner — Samantha Wood*Assistant Examiner* — Vanessa Martinez(74) *Attorney, Agent, or Firm* — iPA & iPM(57) **CLAIM**

The ornamental design for an attachable lamp, as shown and described.

DESCRIPTION

FIG. 1 is a perspective and frontal view of an attachable lamp showing my new design;

FIG. 2 is a perspective view of the attachable lamp from behind;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the attachable lamp with a latch in an opened position.

The broken lines in the drawings depict portions of the attachable lamp that form no part of the claim design.

1 Claim, 7 Drawing Sheets
